UNITED STATES PATENT OFFICE.

HORACE G. STONE, OF CHICAGO, ILLINOIS.

DISTILLATION OF COAL AND OTHER CARBONACEOUS MATERIALS.

1,242,261.

Specification of Letters Patent.

Patented Oct. 9, 1917.

Application filed April 29, 1915. Serial No. 24,623.

To all whom it may concern:

Be it known that I, HORACE G. STONE, a citizen of the United States, residing in Chicago, in the county of Cook and State 5 of Illinois, have invented new and useful Improvements in the Production of Fuel Through the Distillation of Coal and other Carbonaceous Materials, of which the following is a specification.

10 The object of my invention is to extract most of the volatile matter from coal and other carbonaceous materials without extracting the carbon, thus leaving a residuum rich enough in carbon and hydro-carbon to 15 burn without heavy draft, which makes a very desirable and improved fuel.

Other objects and advantages of the invention will be apparent as it is better understood from the following description 20 when considered in connection with the accompanying drawing illustrating a preferred embodiment thereof.

Referring to the drawings,

The figure is the distillation chamber.

25 A is the opening where the coal or other carbonaceous materials are fed into the chamber;

B is the opening where the residuum is taken from the chamber;

30 C are the openings where the uncondensable gas and volatile matter or by-products are taken from the chamber;

C' is the place where the exhausters are attached; and

35 D is the place where the hot gas enters the chamber.

The principal objects in distilling coal and other carbonaceous materials are two-fold; first, to obtain the by-products; second, 40 to obtain good fuel.

To produce such fuel, heat is necessary; and if free oxygen (or air) is not excluded, the carbon will burn and hence no fuel be produced.

45 No "process" for producing the desired result is of any account without the necessary apparatus to carry it out, since the most correct "process" would avail nothing if the coal be put into a bonfire in an open field; hence, the all-important thing is the apparatus, the use of which will produce the desired result.

In attempts at coal distillation, various efforts have been made to exclude the air

and thus save the carbon. Some put the 55 coal into an oven, retort or pipe, and apply heat to the outside.

In my invention I use no such oven, retort or pipe. I put my coal into the distillation chamber and apply hot gas at the bottom 60 thereof, such gas passing directly into and through the mass of coal, and my hot gas is gradually cooled as it passes through the coal which is above it, so that when it reaches the exits from the distillation chamber it has cooled enough to be what is desired.

Others have applied hot gas to coal through complicated and cumbersome devices, sometimes at the top of the coal and 70 sometimes midway of the coal, but for different purposes and with entirely different results from those produced by my invention, wherein I apply the hot gas directly at the bottom of the mass of coal. 75

In my invention I throw aside all complicated and complex devices and build a simple upright distillation chamber, smaller at the top than at the bottom, and into this chamber I put coal until the chamber is 80 full; then, at the base of the chamber I introduce gas at a high temperature. The gas strikes the coal, and the coal begins to heat, and the gas begins to cool, and as the residuum is removed at the bottom the body 85 of coal moves continuously downward from the top to the base of the distillation chamber entirely submerged in a continuous flow of gas.

The gas which enters at the base of the 90 distillation chamber at high temperature distills the coal and cools the gas in transit as the gas passes upward through the mass of coal to the exit, thus providing a means of continuous distillation at a temperature 95 ranging from that at which the gas enters the distillation chamber to the temperature at which the coal enters.

In actual operation, my distillation chamber will be full of coal, and as fast as the 100 residuum is removed from the bottom of the chamber, additional coal will come in at the top of the chamber.

The hot gas will come in at the base of the chamber at a temperature of, say, 1000 105 degrees F., but as the hot gas passes into and through the mass of the coal to the top of the chamber (aided by a positive exhaust

where necessary), it steadily cools until at the top of the chamber it has a temperature of, say, some 200 degrees F.

As the fresh coal comes into the chamber 5 at its top, it soon reaches a temperature which liberates some of the lighter volatile matter; then, as the coal sinks down farther in the chamber it reaches a higher temperature, which liberates more of the volatile 10 matter; and so on, until the coal has reached the place of the maximum temperature at the base of the distillation chamber.

The volatile matters desired as by-products and the uncondensable gas are taken 15 off at one or more openings in the sides of the chamber; and part of the heavy hydrocarbons pass out with the residuum, enriching it and producing the improved fuel which is the object of my invention.

20 All the openings into and out of the distillation chamber are protected by mechanical devices to prevent an excess of free oxygen or air from entering that chamber.

It will be manifest that various changes 25 may be made in the form, construction and arrangement of the parts without departing from the spirit and scope of the invention, or sacrificing any of its material advantages, the form hereinbefore described being 30 merely a preferred embodiment thereof.

I claim:

Apparatus for distilling coal or other carbonaceous material including a distillation chamber whose containing space increases in size from top to bottom, said chamber having an opening located at the upper portion thereof for the passage into the chamber of material to be distilled; means at said opening for preventing admission of an excess of air or free oxygen into 40 the chamber while material is being passed thereinto through said opening, said chamber also having an opening at its base through which coke is discharged; means at said latter opening for preventing admission of an excess of air or free oxygen into 45 the chamber while coke is being passed from said chamber through the latter opening; and means for admitting high temperatured gas into the chamber near the base thereof, 50 said chamber also having an opening in the upper part thereof through which products of distillation are discharged.

In testimony whereof, I affix my signature in presence of two witnesses.

HORACE G. STONE.
